UNITED STATES PATENT OFFICE.

THOMAS K. PETERS, OF LOS ANGELES, CALIFORNIA, ASSIGNOR TO THE COLOR RAY HOLDING CORPORATION, OF DENVER, COLORADO, A CORPORATION OF COLORADO.

ILLUMINATING APPLIANCE.

Application filed January 20, 1928. Serial No. 248,163.

My invention relates to improvements in illuminating appliances in which luminous tubes are employed as the light sources.

An important object is to provide a new and improved arrangement of such tubes in the form of a luminous grid or background composed of one or more bent or contorted tubes, the principal portions of which are spaced, in approximately parallel relation, 10 to provide a substantially close banded illumination of the entire area of the background or grid. Such a luminous grid or background is useful for many purposes, especially in appliances of the character usually called "illuminated signs."

A further object of the invention is to utilize such a luminous grid or background in an appliance of that class by providing a front plate or screen which is relatively opaque, and provided with relatively translucent or transparent areas constituting a design illuminated by the grid or background; or as otherwise stated, through 20 which the grid or background is visible, thus presenting design areas illuminated by more or less closely spaced bands of light emitted from the luminous tubing.

A further object is to provide a front plate or screen in the form of separate, 30 changeable or interchangeable sections, each of which bears a portion of a design, so that for example when the design consists of letters or other indicia, any desired words or indicia may be set up by positioning proper screen sections in the sign casing.

While such appliances are conveniently designated as "signs", they need not have a utilitarian character but may be for decorative or scientific purposes, in which case the 40 relatively transparent areas on the front plate or screen may constitute a decorative design in the nature of a picture.

A further important object is to provide or utilize a plurality of luminous tubes of 45 different color characteristics in a single luminous grid or background, with suitable means for selectively or simultaneously electrically energizing the different tubes, whereby a plurality of simple or blended 50 color effects are obtained. Thus, using two tubes, one of which emits blue and the other red luminosity, three color effects are obtained with the two tubes, namely, the simple or primary colors red and blue, and the blended or complex color lilac. This fea-

ture of the invention may be utilized in connection with any of the other features previously mentioned, such as the front plate or screen bearing a design to be illuminated by the multiple color grid or background, with 60 any of the other variations mentioned above or hereinafter.

For the sake of simplicity, I refer above to luminous tubes. The well known neon tube is an example, consisting of a relatively 65 long cylindrical tube having bulbous ends containing electrodes, and supplied with neon gas at suitable pressure, the electrodes being in circuit with a high-potential transformer, whereby the gas is energized or ionized and light of a characteristic orange-pink color is emitted. Other gases including active diatomic gases such as nitrogen, 70 hydrogen, oxygen, etc., and other inert, monatomic gases such as helium, argon, 75 xenon and krypton (besides neon) are used in similar tubes. Such tubes are analogous to Geisseler tubes, and the particular characteristics of the tubes per se are not involved in the present invention. 80

When different color effects are desired they may be produced by the different color characteristics of different gases used in the respective tubes, by tinting the tubes themselves, silvering them, impregnating the 85 glass with various metallic elements, or in other known or suitable ways.

The characteristics and advantages of the invention are further sufficiently explained in connection with the following detail description of the accompanying drawings, 90 which illustrate certain representative embodiments. After considering these examples, skilled persons will understand that many variations may be made without departing from the principles involved, and I contemplate the employment of any structures that are properly within the scope of the appended claims. 95

In the drawing:

Fig. 1 is a front elevation, with some parts in section, of apparatus embodying the invention in one form.

Fig. 2 is a section at 2-2 Fig. 1.

Fig. 3 is a section at 3-3, Fig. 1.

Fig. 4 is a similar section showing a modified form of color background or grid, employing a single tube.

Fig. 5 is an elevation of a modified tube arrangement or assembly constituting an-

other form of color background or grid, approximately one and one-half inches therefrom.

Fig. 6 is a bottom plan of the same.

Fig. 7 is an elevation of another tube arrangement or assembly.

Fig. 8 is a bottom plan of the same.

Fig. 9 is a view, similar to Figs. 6 or 8, of another modified tube or grid arrangement.

Fig. 10 is an elevation of still another tube arrangement or assembly.

Fig. 11 is a top plan of the same.

Fig. 12 is a perspective view showing a theatre marquee.

The principal feature of the invention is what I call a color background or composite grid consisting of one or more tubes which are practically Geisseler tubes curved, bent or contorted to produce approximately parallel portions, arranged nearly or exactly in one plane, so that the area of the background is well covered with the moderately spaced tube portions; or in other words, the grid area is composed of approximately parallel or moderately spaced bands of light emitted by the luminous medium within the tube. Thus, in Figs. 1, 2 and 3, the composite grid element or color background 1 consists of two grid tubes 2 and 3, each of which has bulbous end portions 4 and 5, respectively. In each bulb is an electrode having an outside terminal 6. Each tube is filled with a suitable gaseous medium such as one of those above mentioned, and when the two terminals are connected to the terminals of a high frequency or high-potential transformer, the contents is ionized and emits light of characteristic color, depending upon the nature of the gas, or characteristics of the glass in the tube itself. Figs. 1 to 3 illustrate one characteristic way in which the grid element is substantially covered with the illuminated bands, namely, by forming or bending grid tube 2 so that it consists of a plurality of spaced parallel main portions 7 connected by end bends 8 which may be in the plans of the main portions. The other grid tube consists of spaced parallel main portions 9 interspaced with the main portions of grid tube 2, and in the same plane, and the main portions of grid tube 3 are connected by bends or bridge portions 10, bent or offset substantially at right angles to the plane of the grid so as to pass over or bridge the intermediate portions of the other tube. As will be observed (Figures 2 and 3), the background or grid is arranged relatively close to the screen, i. e., the screen and tubes are so spaced as to obtain upon the screen the visually distinguishable bands or striped effect desired.

I have found that the best results are obtained by spacing the tubes in close proximity to the screen or stencil, say within

other form of color background or grid, approximately one and one-half inches therefrom.

When two or any other plurality of tubes are used, they are usually arranged to emit light of different colors either by charging the tubes, comprising the grids, with different gases or by treating the glass of the tubes themselves in ways above mentioned to provide the different colors or tints.

Thus, in Figs. 1 to 3, tube 2 may be a neon tube and will in that case emit the characteristic orange-pink color, and tube 3 may

be charged with gas or otherwise provided with means by which it emits blue light.

When either tube is separately energized the illuminated background or grid therefor consists principally of parallel bands of a single simple light, either orange-pink or blue, and when both are simultaneously en-

ergized there is produced practically a blend of the simple colors, or an approximately

lilac illumination of the background area.

Such luminous backgrounds or grids are useful for many purposes, a sufficient example of utility being given in Figs. 1 to

3, in which a composite grid is arranged in a sign box 15. The straight tube portions are supported in properly spaced relations by vertical racks 16. In the rear of the

box is a high-potential transformer 17, the secondary leads 18 of which are in circuit with contacts 19 of a rotary flasher 20.

Brushes 21 are connected to the respective tube terminals 6 and the contacts are ar-

ranged so that the tubes are energized singly or simultaneously, the order of energizing being, of course, variable by suitable rear-

rangements of the contacts on the flasher drum. The flasher is driven by a motor 22,

and the transformer and motor are supplied with current from any suitable power line

23 under the control of a switch 24. In-

stead of such automatic controlling means, hand control by individual switches may in

some cases be provided.

The housing 15 is provided along its upper and lower front edges with channels 25 to

slidably receive changeable or interchangeable sign sections 26 of any suitable sheet material, and generally relatively opaque.

Thus, if the sign sections are of metal they are naturally completely opaque, while if of

glass or analogous material they may be rendered approximately or completely

opaque by coating with paint or other ma-

terial, in all their areas except the design areas presently referred to. Each screen sec-

tion includes a design area 27 which may be a letter or other character, or a part of a

complete decorative design, this being pro-

vided, in the case of a sheet of opaque ma-

terial, by cutting out the material to form a

stencil opening, or in the case of material

which is coated, by leaving the design area

uncoated so that it is translucent or trans-

parent, depending for example upon whether it is made of clear, or opalescent pebbled or frosted glass. It is evident, without elaborate explanation, that by the described means practically any desired legend or design may be set up on the front face of the sign box. When the design areas are transparent, the grid or background will be observed through such areas, producing variable color effects as sufficiently above explained, including simple colors or blends. When the design areas are not transparent, but translucent, the light emitted by the separate tubes of the grid will be more or less blended, and diffused, and in this way different color effects may be produced.

In some cases a partition such as a sheet of transparent or translucent glass 28 may be inserted in vertical guide channels 29 between the design or screen and the color background or grid. This provides for substantially complete closure of the sign box, whether or not the sign sections are in position. Additionally, a light reflecting member 29' may be arranged in the rear of the background or grid, and preferably has the exposed face thereof suitably treated or finished to produce in conjunction with the tubes any desired color or pattern effect. Fig. 12 shows a changeable or interchangeable sign structure, of the character just described, incorporated in the front of a theatre marquee 30. Either side of the canopy may have a stenciled screen 31 provided with stencil or design areas 32 analogous to those already described, but arranged as a changeable or nonchangeable sign or design. The foregoing are only two examples of the many adaptations or uses of the color grid or background.

Fig. 4 illustrates a grid consisting of a single tube 2 which may be substantially the same as the tube 2 of the previous example, except that its main portions 7 may be, if desired, more closely spaced than in the previous instance. Such a single tube grid gives only a single color effect, but provides a distinctly new and improved sign or illuminated design in combination with a front or screen having characteristics of the previous examples, and as sufficiently illustrated in Fig. 4.

Figs. 5 and 6 show a grid composed of three tubes, of which tubes 2 and 3 may be substantially the same as in Figs. 1 to 3. The additional tube 40 has its straight parallel portions interspaced with those of the other two tubes, and also has bends or bridge portions 41 to pass over the straight sections of the other tubes, as in the case of tube 3 of this and the previous examples. There is thus provided a color background or composite grid 45 composed of relatively closely spaced parallel tube portions consisting of parts of three distinct luminous tubes.

Each of the tubes is desirably designed to emit light of a different color, and suitable control means may be provided on the general plan of Fig. 2, but with suitable contacts on the distributor arranged to control the three tubes so that they are energized singly or in any combination, thus giving a total of seven color effects by the use of only three tubes. When the straight tube portions are properly spaced and any two of them are simultaneously energized, the resulting color effect is substantially a blend of the component colors. Figs. 5 and 6 also illustrate that the straight tube portions may, if desired, be arranged, vertically instead of horizontally, as in the previous instance.

Fig. 7 shows a grid arrangement substantially similar to Figs. 1 to 3, except that the straight tube portions are arranged vertically instead of horizontally.

Fig. 9 shows a modification in which the straight portions of each tube are connected by bends or bridging members 50, all of which are bent at right angles to the planes of the respective straight portions; thus bridging members 50 of grid tubes 2 and 3 are bent outwardly in opposite directions from the plane of the straight portions, although the straight portions all lie in the same plane.

Figs. 10 and 11 illustrate a modification in which two tubes 60 and 61 have their straight portions 62 and 63, respectively, arranged at right angles to each other, forming in effect a checkerboard color background or grid. In this arrangement it is practically impossible to have the straight tube portions in one plane, but they may be, as clearly shown in Fig. 11, very nearly in one plane. When two luminous tubes, arranged as shown in these figures, emit light of different colors, the effect when either tube is illuminated singly is substantially like that of the previous examples, but when the tubes are energized simultaneously, the simple colors blend at each crossing or intersection of the different tube portions while the intermediate straight portions of the respective tubes emit simple or unblended light, thus providing a distinctly novel color effect, different from the effects produced in the previous examples wherein the principal tube portions are substantially parallel.

It is to be understood that the terms "background" or "grid" are employed in a generic sense and include any arrangement of the tubes which will produce the effects desired. It is obvious that the forms illustrated in Figures 5 to 11 inclusive all have a common characteristic, namely a plurality of gas containing chambers or passages, which are non-communicating. In other words, these forms illustrate the generic idea of providing a background embodying a multiplicity of gas containing passages or cham-

bers closed from one another. As has been explained, a very important advantage of this construction resides in the fact that the non-communicating compartments or passages permit the obtaining of different color effects, for instance, by the use of different gases in the different passages.

An important feature of my invention is that I provide for the illumination of signs by means which contemplate defining the pattern, at the light source itself, in a continuous and definite pattern, as distinguished from flashing vari-colored lights, or blending lights of different colors and am able to accomplish, with a simple change of light grids, a result which cannot be reached with the mechanical contrivances for flashing, in sequence, the different colors of signs now in use.

Evidently many other variations may be made both as to the general form or arrangement of the color grids and by utilization in signs or analogous illumination apparatus, as will be sufficiently understood by skilled persons, from the examples given.

What I claim is:

1. In an illuminating appliance of the class described, a background composed of luminous tubing, the main portions of which are arranged in spaced relation so that the area of the background is well covered by bands of light emitted from the tube portions, and a relatively opaque screen located in front of the background and provided with relatively translucent patterned areas constituting a design illuminated by the background, said translucent areas being disposed in front of said tubes and relatively close thereto, whereby to provide, when the tubes are made luminous, a pattern composed of bands or stripes of light visually distinguishable over said areas.

2. An illuminating device of the class described, comprising a grid composed of non-communicating luminous gas filled tubing, electrodes for making the gas in said tubing luminous, a substantially flat light reflecting member in the rear of said tubing, an opaque screen in front of said grid, said screen being provided with relatively translucent areas behind which said grid is disposed, said grid and areas being relatively arranged to provide, when the tubing is made luminous, a design composed of bands or stripes of intense light and of a color characteristic of the gas contained in said tubing.

3. An illuminating device of the class described, comprising grids composed of luminous gas filled tubes, portions of the tubes of one grid being disposed between the tubes of the other grid, electrodes for making the gas in said tubes luminous, and an opaque screen in front of the tubes and in relatively close proximity thereto, said screen

being provided with designed relatively translucent areas, whereby to provide, when the tubes are made luminous, diffused bands or stripes of intense light and of colors characteristic of the gas contained in said tubes.

4. An illuminating device of the class described, comprising a plurality of grids, each composed of luminous gas filled tubes, portions of the tubes of the different grids being disposed between one another in substantially a common plane, electrodes for making the gas in said tubes luminous, and an opaque screen in front of the grid and in relatively close proximity thereto, said screen being provided with designed relatively translucent areas in front of said tubes, whereby to provide, when the tubes are made luminous, diffused bands or stripes of intense light and of spectral colors characteristic of the gas contained in said tubes.

5. An illuminating device of the class described, comprising a background composed of non-communicating luminous gas filled tubes, electrodes for making said tubes luminous, means in the respective tubes for emitting different colors or tints, and an opaque screen in front of said tubes and in close proximity thereto and provided with designed relatively translucent areas, said areas composed of visually distinguishable bands or stripes of intense light and of colors characteristic of the gas contained in said tubes.

6. An illuminating device of the class described, comprising grids composed of a plurality of non-communicating luminous tubes having electrodes for making the same luminous, said grids having main portions which are substantially parallel, and other portions angularly disposed relative to the main portions, a substantially flat light reflecting member in the rear of said tubes, and a relatively opaque screen closely positioned in front of the tubes and provided with relatively translucent areas arranged in front of the grid.

7. An illuminating device of the class described, comprising a background composed of a plurality of non-communicating luminous tubes having electrodes, certain of said tubes having main portions connected by bridge portions, other of said tubes having portions interspaced between said main portions, means in said tubes for emitting luminous rays of different colors or tints, and means for causing illumination of the tubes separately for producing different color effects.

8. An illuminating device of the class described, comprising a background composed of a plurality of non-communicating luminous tubes having electrodes, certain of said tubes having main portions connected by bridge portions, other of said tubes having

portions interspaced between said main portions, means in said tubes for emitting luminous rays of different colors or tints, and means for causing illumination of the tubes 5 separately and simultaneously for producing different color effects.

9. An illuminating device of the class described, comprising a background composed of a plurality of non-communicating luminous tubes having electrodes, means in the tubes for emitting luminous rays of different colors or tints, certain of said tubes having main portions connected to one another, others of said tubes having main portions 10 interspaced between said first mentioned portions, means in said tubes for emitting luminous rays of different colors or tints, means for causing illumination of the tubes simultaneously for blended color effects, and 15 an opaque screen closely positioned in front 20

of the background and provided with designed translucent areas in front of the background.

10. An illuminating device of the class described comprising a background composed of a plurality of non-communicating luminous tubes having electrodes, certain of said tubes having main portions connected by bridge portions, other of said tubes having portions interspaced between said main 25 portions, means in said tubes for emitting luminous rays of different colors or tints, a light reflecting member positioned in the rear end in close proximity to said tubes, and means for causing illumination of the tubes separately for producing different 30 color effects.

Signed at New York city, New York, this 18th day of January, 1928.

THOMAS K. PETERS.
